Patented May 14, 1968

211,014

BODY FOR A UTILITY VEHICLE

William T. Donofrio, Toledo, Ohio, assignor to Donofrio
& Company, Toledo, Ohio, a corporation of Ohio

Filed Aug. 31, 1967, Ser. No. 8,451

Term of patent 14 years

(Cl. D14—3)

FIG-1-

FIG-2-

FIG-3-

FIG-5-

FIG-4-

FIG-6-

FIG-7-

FIG. 8 -

FIG. 9 -

FIG. 10 -

FIG. 11 -

FIG. 1 is a front quarter view in perspective of a body for a utility vehicle showing my new design;

FIG. 2 is a side elevational view thereof on a smaller scale;

FIG. 3 is a plan view thereof;

FIG. 4 is a front elevational view thereof;

FIG. 5 is a rear elevational view thereof;

FIG. 6 is a front quarter perspective view similar to FIG. 1 but showing the body with the cab removed;

FIG. 7 is a rear quarter view in perspective of the body as shown in FIG. 6;

FIG. 8 is a plan view of the body as shown in FIG. 6;

FIG. 9 is a side elevational view of the body as shown in FIG. 6;

FIG. 10 is a rear elevational view of the body as shown in FIG. 6; and

FIG. 11 is a front elevational view of the body as shown in FIG. 6.

The portions shown in broken lines are included for illustrative purposes only.

I claim:

The ornamental design for a body for a utility vehicle, as shown and described.
